(57) **CLAIM**

The ornamental design for a fishing net frame, as shown and described in the drawings and specification.

DESCRIPTION

FIG. 1 is a top front isometric view of a new design for a fishing net frame, with environment.

FIG. 2 is a top front isometric view of the design of FIG. 1. FIG. 3 is a bottom rear isometric view of the design of FIG. 1.

FIG. 4 is a front view of the design of FIG. 1.

FIG. 5 is a rear view of the design of FIG. 1.

FIG. 6 is a left side view of the design of FIG. 1.

FIG. 7 is a right side view of the design of FIG. 1.

FIG. 8 is a top view of the design of FIG. 1.

FIG. 9 is a bottom view of the design of FIG. 1; and, FIG. 10 is a cross-sectional view of the design of FIG. 1. The broken line showing of portions of the fishing net frame is included for the purpose of illustrating only and forms no part of the claimed design.
